John O. Brady
ATTORNEY

UNITED STATES PATENT OFFICE

CLINTON W. HOUGH, OF BOONVILLE, NEW YORK, ASSIGNOR, BY MESNE ASSIGNMENTS,
TO FEDERAL TELEGRAPH COMPANY, A CORPORATION OF CALIFORNIA

ELECTRICAL PHONOGRAPH ATTACHMENT FOR WIRED RADIORECEIVERS

Application filed February 16, 1928. Serial No. 254,874.

My invention relates broadly to wired radio receiving apparatus and more particularly to a phonograph attachment for wired radio receiving apparatus.

5 One of the objects of my invention is to provide a construction of attachment for a wired radio receiver whereby the audio frequency amplification circuits of the wired radio receiver may be utilized in connection 10 with a phonograph pick-up for operation of the loud speaker reproducer normally actuated by the wired radio receiving apparatus.

Another object of my invention is to provide a construction of attachment for a wired 15 radio receiver cabinet which attachment may be readily mounted upon or removed from the top of the wired radio receiver cabinet and connections automatically established with the audio frequency amplification circuits.

20 Still another object of my invention is to provide an electric phonograph attachment for a wired radio receiver wherein the parts of the electric phonograph are mounted within a housing which may be readily adapted 25 to the top of a wired radio receiver cabinet utilizing the audio frequency amplification circuit of the wired radio receiver for amplification of energy picked up by the phonograph pick-up device, enabling such energy 30 to be reproduced through the same loud speaker normally employed for the wired radio receiver.

Other and further objects of my invention reside in the construction and arrangement 35 of parts for the phonograph attachment for a wired radio receiver, as set forth more clearly in the specification hereinafter following by reference to the accompanying drawings in which:

40 Figure 1 is a front view of the wired radio receiver and phonograph attachment mounted thereon; Fig. 2 is a side elevation of the wired radio receiver showing the phonograph attachment mounted thereon; Fig. 3 45 is a fragmentary view of the top of the wired radio receiver showing the phonographic attachment in cross section and mounted upon the top of the wired radio receiver; and Fig. 4 is a top plan view of the phonographic attachment for a wired radio receiver with the

top of the attachment swung back to enable the parts to be viewed.

Referring to the drawings in more detail, reference character 1 designates the cabinet which houses the wired radio receiving apparatus. The loud speaker is disposed behind the grill work 2 in the wired radio receiver, and suitable controls 3 and 4 extend from the front of the wired radio cabinet. The top of the wired radio received cabinet 55 designated at 5 is provided with insulated bushings 6 through which metal bushings 7 extend terminating in spring arms 8. The electric phonographic attachment is housed within the enclosure constituted by side walls 60 9 and base 10. The base 10 carries turn-table 11 mounted upon pivot 12. The turn-table 11 forms a support for a phonograph record 14 which is driven by rotation of the turn-table 11 through the friction drive 15 operated from motor 16. A standard 17 is mounted upon the base 10 and carries arm 18 pivotally mounted thereon, which in turn carries the phonograph pick-up device 19 having a stylus 20 which engages the grooves of sound 70 record 14. The conductors from the phonograph pick-up device 19 extend through the pivoted arm 18 and connect through wires 20 and 21 with binding posts 22 and 23. These binding posts are mounted upon the base 10 75 and have projecting rod members 24 and 25 protruding therefrom located in such positions as to engage the metallic sleeves 7 and the spring arms 8 at the ends thereof and establish wiping contact therewith. The 80 sleeves 7 connect through conductors represented at 27 and 28 with the audio frequency amplification apparatus within the wired radio receiver cabinet 1. To facilitate the centering of the attachment 9 upon the 85 wired radio receiver I may provide centering pins represented at 30 adjacent each corner of the attachment, which pins may project into the top of the wired radio receiver cabinet for securing the attachment in position 90 with respect to the cabinet. The attachment 9 is provided with a top cover 31 which is hinged at 32 to the wired radio receiver cabinet 1.

It will be observed that the wired radio re- 100

ceiver may be supplied with sockets formed in the top thereof, which sockets are arranged to receive the prongs 24 and 25 of the phonograph pick-up attachment which may be supplied at the choice of the subscriber to the wired radio service who may be furnished with the wired radio receiver 1. The assembly of the electric phonograph attachment upon the wired radio receiver is entirely optional with the wired radio subscriber.

When it is desired to reproduce sound records by means of the phonograph pick-up device the cabinet housing this pick-up device, being separate from the radio receiving set is superimposed upon the set. The rod members which project from the cabinet are caused to contact with the sleeve members which are provided in the radio receiving set cabinet. Connections between the radio receiving set and the wired radio distribution circuit are interrupted by removing a wall plug from the wall outlet, such as is commonly employed in wired radio distribution circuits, and the phonograph pick-up device together with the audio frequency amplifier may be used for reproduction of sound records. When the apparatus is to be used for the reception of wired radio signals the phonograph pick-up device is removed from the radio receiver and the plug is inserted into the wall outlet or receptacle. The equipment is then ready for use as a wired radio receiving set.

While I have described our invention in one of its preferred embodiments, I desire it to be understood that modifications may be made and that no limitations upon my invention are intended other than are imposed by the scope of the appended claims.

What I claim as new and desire to secure by Letters Patent of the United States is as follows:

1. An electric phonograph attachment for wired radio receivers comprising a casing arranged to be mounted upon the top of a wired radio receiver cabinet, phonograph mechanism carried by said casing including an electrical pick-up device and a pair of protruding prongs connected to said pick-up device and mounted on said casing insertable into said wired radio receiver cabinet for establishing connection with the input circuit of the audio frequency amplifier of said wired radio receiver within said cabinet.

2. An electric phonograph attachment for wired radio receivers comprising in combination a wired radio receiver, a cabinet for said receiver, socket members carried by said cabinet, said wired radio receiver comprising an audio frequency amplifier, the input circuit of said amplifier being connected with said socket members, a casing including electric phonograph mechanism and substantially corresponding in contour to the shape of said wired radio receiver cabinet, pins extending from said casing and engageable with said

sockets for establishing connection between the phonograph mechanism within said casing and the amplification circuits within said wired radio receiver cabinet.

3. An electric phonograph attachment for wired radio receivers comprising a wired radio receiver cabinet, a pair of socket members positioned at the top of said wired radio receiver cabinet, amplification circuits within said wired radio receiver cabinet connected with said socket members, an electric phonograph pick-up apparatus, a casing including said electric phonograph pick-up apparatus and having a pair of downwardly projecting prongs on the base thereof located in position to engage the socket members at the top of said wired radio receiver cabinet for establishing electrical connection between the electric phonograph pick-up apparatus and the amplification circuits in said wired radio receiver cabinet.

4. An electric phonograph attachment for wired radio receivers comprising a wired radio receiver cabinet having amplification circuits therein, separate socket members mounted at the top of said wired radio receiver cabinet, one of said socket members being disposed adjacent one end of said wired radio receiver cabinet and the other of said socket members being disposed adjacent the opposite end of said wired radio receiver cabinet, a casing substantially conforming in contour with the shape of said wired radio receiver cabinet, electric phonograph mechanism carried within said casing, and a pair of downwardly protruding prongs extending from the base of said casing in positions adjacent opposite ends thereof for engaging the sockets in the top of said wired radio receiver cabinet and establishing electrical connection between the electrical phonograph pick-up mechanism in said casing and the amplification circuits in said wired radio receiver cabinet.

In testimony whereof I affix my signature. 110
CLINTON W. HOUGH.
